UNITED STATES PATENT OFFICE.

AMASA H. WILSON, OF CHICAGO, ILLINOIS.

SPRING-HINGE.

SPECIFICATION forming part of Letters Patent No. 518,639, dated April 24, 1894.

Application filed August 3, 1893. Serial No. 482,230. (No model.)

To all whom it may concern:

Be it known that I, AMASA H. WILSON, a citizen of the United States of America, residing at Chicago, in the county of Cook and State of Illinois, have invented certain new and useful Improvements in Spring-Hinges for Doors, of which the following is a specification.

My invention relates to a certain new and improved combination in spring hinges for doors whereby greater simplicity, cheapness and a neater appearance are obtained by making the hinges themselves take the place of certain parts commonly employed in a doorspring and also by utilizing a portion of the door spring to take the place of certain parts of the hinges.

My invention will be readily understood from the drawings presented herewith, in which—

Figure 1 is an elevation of a door provided with my improvements. Fig. 2 is a horizontal section looking down upon line 2—2 Fig. 1. Fig. 3 is a detached side view of the upper hinge, and Fig. 4 a horizontal section in line 4—4 of Fig. 1.

The door is represented at A and the casing at B. The door is hinged upon the casing by means of two butt hinges of the simplest form such as have been in common use. These hinges are, however, not provided with the ordinary pins or pintles the function of the latter being performed by a torsion rod D, extending between and through the hinges so that the knuckles of the latter may turn upon it. This torsion rod D, is secured against rotation in the leaf of the hinge, C', which is secured to the door, by means of a triangular portion d, fitting in a correspondingly shaped hole, c, in the leaf. The upper end of the rod D, is also triangular in cross section and has a toothed disk d', fitted to said triangular portion and provided around its periphery with a series of notches adapted to engage with a shoulder c', upon the leaf of the hinge C, which is secured to the casing. The disk d', slides up and down upon the triangular

upper end of the rod D, so that it may be engaged with or disengaged from the shoulder c', at will. The opposite leaf of the hinge C, 50 is cut away at c² so as not to interfere with the toothed disk.

In applying the invention to a door the two hinges are secured to the door and casing, respectively, in the ordinary manner, the rod 55 is inserted in place and turned up to the desired tension by means of a wrench fitted to the upper end. When the necessary strength is obtained the toothed disk is slipped down over the shoulder c', securely engaging the torsion rod therewith. As this rod may be twisted in either direction it is adapted equally as well to a door swung from either side.

By means of the combination effected by my invention it should be noticed that there 65 is a great saving in the number of parts required in the use of a torsion spring of this sort. In the first place the rod requires no end attachment to the door and casing as such attachments are furnished by the ordinary leaves of the hinges. In the second place the pins or pintles of the hinge are done away with, their functions being performed by the ends of the torsion rod.

I claim as new and desire to secure by Letters Patent—

1. In spring hinges, the combination of two hinges with a torsion rod in a single piece extending between said hinges and acting as a common pintle therefor, said rod being secured to opposite leaves one upon each hinge and placed under tension to swing the door. 80

2. In spring hinges, the combination of two hinges with a torsion rod in a single piece extending through and between said hinges and acting as a pintle therefor, said rod being secured to opposite leaves, one upon each hinge, the engagement with one of said leaves being secured by means of an adjusting device substantially as shown and described. 85

AMASA H. WILSON.
